Primary Examiner — Richard Edgar*Assistant Examiner* — Nader Abadir(74) *Attorney, Agent, or Firm* — Sean S. Swidler; Swidler Law Group, LLC(57) **CLAIM**

The ornamental design for a bar tool, as shown and described.

DESCRIPTION

FIG. 1 is a front, top, and right perspective view of a bar tool showing my design;

FIG. 2 is a front elevation view of thereof;

FIG. 3 is a first rear elevation view thereof, with coil spring shown;

FIG. 4 is a second rear elevation view thereof, with no coil spring shown;

FIG. 5 is a left-side elevation view thereof;

FIG. 6 is a right-side elevation view thereof;

FIG. 7 is a top plan view thereof; and,

FIG. 8 is a bottom elevation view thereof.

The broken lines shown throughout these figures depict portions of the bar tool that form no part of the claimed design.

1 Claim, 6 Drawing Sheets
